DAVID E. MACCABEE, OF DAYTON, OHIO, ASSIGNOR TO FRIGIDAIRE CORPORATION, OF DAYTON, OHIO, A CORPORATION OF DELAWARE

REFRIGERATING APPARATUS

Application filed March 31, 1930. Serial No. 440,493.

This invention relates to refrigerating apparatus and particularly to soda fountains and similar devices in which various commodities of different characters are maintained at different temperatures.

One of the objects of the invention is to provide a simple and economical refrigerating apparatus particularly adapted to soda fountains.

Another object of the invention is to provide an improved and simplified arrangement for maintaining a number of different compartments at different temperatures by means of a single refrigerating system.

More specifically it is an object of the invention to operate a plurality of evaporating elements in series and to provide an improved arrangement for controlling the amount of refrigerant which is evaporated in each successive evaporator of the series.

Further objects and advantages of the present invention will be apparent from the following description, reference being had to the accompanying drawings, wherein a preferred form of the present invention is clearly shown.

In the drawings:

Fig. 1 is a diagram of a refrigerating system embodying the invention; and

Fig. 2 is a vertical longitudinal section of a portion of an evaporator.

It is usual to provide soda fountains with a compartment for storing ice cream which should be kept at a temperature of 7° F. or less, a compartment for storing and cooling water on draft which should be maintained at a temperature between 35° and 40° and a compartment for containers of fountain syrups, fruit juices and the like, commonly called a syrup rail, which should be maintained at a temperature between 35° and 55° F.

One of the systems heretofore used for refrigerating soda fountains includes a condensing element having a compressor 10 operated by an electric motor 12 for withdrawing gaseous refrigerant from a vapor return line 14, compressing the refrigerant so that it will be liquefied in a condenser 16 from which it flows to a receiver or reservoir 18.

Liquid refrigerant is supplied from the reservoir by a conduit 20 to an evaporator 22 called the water coil located in a compartment 24 and usually immersed in sweet water for cooling circulating drinking water. 55 From the evaporator 22 liquid refrigerant is led by a conduit 26 to a second evaporator 28 called the ice cream coil located in a compartment 30 and usually immersed in brine for cooling ice cream. The conduit 26 includes a portion 32 disposed in a compartment 34 usually called a syrup rail, the conduit 32 acting as an evaporator to cool fountain syrups. The vapor return conduit 14 has an unobstructed connection with a conduit 36 by which gaseous refrigerant is withdrawn from the evaporator 28. The evaporator 22 is connected to the conduit 14 by a vapor return conduit 38 through a pressure regulating valve 40 which may be constructed for example as shown in the application of Ernest Dickey, Serial No. 753,048 filed December 1, 1924. The motor 12 ordinarily runs intermittently being started and stopped automatically in response to the condition of the refrigerating system by a pressure-responsive switch 42 connected to the vapor return conduit 14. 70 75

Each of the evaporators is of the flooded type in which the pressure of the refrigerant bears a direct relation to the temperature of the evaporator and each includes a header or reservoir for liquid refrigerant 50, which forms a gas and liquid separating chamber, to which liquid refrigerant is admitted from an inlet connection 52 through the orifice 53 under the control of a needle valve 54 operated by a float 56 to maintain a constant level of refrigerant in the reservoir. Gaseous refrigerant is withdrawn from the upper part of the reservoir by conduit 36 or 38 through a vapor connection 58 and a tube 60 having its inlet or open end 62 disposed above the maximum level of liquid in the chamber 50. This tube has an opening 64 in its side wall 85 below the level of the mouth 62 which opening permits the draining of oil, collecting on top of the liquid refrigerant back to the compressor through the vapor return conduit. Depending from the chamber 50 are any suit- 100

able number of evaporating or circulating tubes 66.

The refrigerant used is preferably sulfur dioxide with which is circulated lubricating oil, as is known.

5 As described so far the evaporators 22 and 28 are identical. In addition to the features enumerated above the evaporator 22 is provided with a fitting 70 through which the 10 vapor connection 58 communicates with the tube 60 and which is provided with a conduit connection 72 communicating with a small tube 74 but not communicating with the vapor conduit 60. The tube 74 is passed 15 through the tube 60 and extends into the reservoir 50 below the level of liquid refrigerant. The conduit 26 leads from the connection 72 to the liquid inlet connection 52 of the evaporator 28 and forms the sole source 20 of supply of refrigerant to that evaporator.

When the compressor is operating, gaseous refrigerant is withdrawn from both the evaporators, the pressure regulating device 40 operating to maintain any desired difference 25 in pressure between the evaporators 22 and 28. The switch 42 may be set to start the compressor when the pressure in the vapor return line is high, for example 5 pounds per square inch gauge and to stop the compressor when the pressure has reached the 30 predetermined low value, for example a vacuum of 18 inches of mercury. The pressure regulating device restricts or prevents communication between the vapor conduit 38 35 and the vapor conduit 14 whenever the pressure in the vapor conduit 38 reaches a predetermined low value, for example 2 pounds per square inch gauge. This arrangement maintains a suitable temperature, for example 40 40° in the water compartment, and a lower temperature, for example 0° or below in the ice cream compartment.

It will be appreciated that due to the difference in pressure between the water coil 45 and ice cream coil, liquid refrigerant will be forced from the chamber 50 of the water coil through the small tube 74 and through the conduit 26 to the inlet 52 of the ice cream coil, and whenever the float valve 56 of the 50 ice cream coil is open liquid refrigerant will be admitted to that coil.

Theoretically a part of the liquid refrigerant passing through the conduit 26 is evaporated in the conduit 32 to provide refrigeration for the syrup rail, and a part of the liquid passes into the evaporator 28 to be vaporized there to provide refrigeration for the ice cream compartment. In practice considerable operating difficulty has been 55 60 65 countered due to the fact that not enough refrigerant in liquid form reaches the ice cream coil. This has two undesirable results, first, a sufficient amount of refrigeration is not provided for the ice cream compartment and second, due to the fact that liquid

level in the chamber 50 may never be high enough to drain oil through the opening 60, the refrigerant evaporates leaving the oil in the chamber 50, which eventually becomes filled with oil to the exclusion of refrigerant, 70 or as is known in the trade, oil-logged.

My investigations lead me to believe that this starving of the ice cream coil is due to two causes. First, when the compressor starts the pressures in the two evaporators 75 are practically equal since the pressure regulating device 40 never completely closes and the pressures equalize during the idle periods of the compressor. Therefore the difference in pressure between the two evaporators 80 which is required to force a sufficient quantity of liquid into the evaporator 28 is not attained until after a considerable period of operation of the compressor. The pressure differential therefore varies from zero at the 85 beginning of an operating period to the maximum at the end of an operating period. During this time the quantity of liquid supplied to the evaporator 28 may be insufficient 90 to provide for the refrigerating demand on that evaporator. Second, on starting the apparatus for the first time, or after a period of shut-down when the conduit 32 has become quite warm, the liquid which is initially forced into the conduit 32 flashes into vapor 95 and builds up a pressure sufficient to prevent the flow of liquid from the evaporator 22 to the evaporator 28. Since the only communication between the conduit 32 and the compressor for the withdrawal of vapor is the small float valve orifice 53 in the ice cream coil this pressure may never be reduced to a sufficiently low value to supply liquid to the evaporator 28. Moreover the flashing of refrigerant into vapor in the conduit 32 may 105 blow back liquid refrigerant through the connection 74 and thus empty the tube of liquid.

My invention overcomes the objections to the above described system by means of a receiver or reservoir 80 between the water coil and the syrup rail and above the level of the ice cream coil. This reservoir has its inlet connection 82 at the top and its outlet connection 84 at the bottom so that any liquid reaching the reservoir cannot be blown back as liquid into the water coil but can drain or be forced to the ice cream coil. If desired the reservoir 80 may be insulated in order that liquid refrigerant admitted thereto may not be flashed into vapor. Preferably the portion 86 of the conduit 26 between the water coil and the reservoir is also insulated and is provided with a check valve 88 which prevents any return flow of refrigerant or the transmission of any pressure 110 115 120 125 from the syrup rail to the water coil.

By this arrangement whenever the compressor has produced a high pressure differential between the ice cream coil and the water coil, refrigerant may fill the reservoir 120

80 because refrigerant can flow through the connection 74 faster than through the float valve of the ice cream coil. During this period any desired quantity of liquid refrigerant may be stored in the reservoir 80 which 5 is suitably proportioned for this purpose, and this supply of liquid may drain by gravity to the ice cream coil whenever the float valve is open, whether or not the compressor is operating. This supplies the ice cream coil with the requisite quantity of liquid refrigerant.

15 While the form of embodiment of the invention as herein disclosed, constitutes a preferred form, it is to be understood that other forms might be adopted, all coming within the scope of the claims which follow.

20 What is claimed is as follows:

25 1. Refrigerating apparatus comprising in combination a relatively high pressure evaporator including a reservoir for liquid refrigerant, a relatively low pressure evaporator including a reservoir for liquid refrigerant, and a conduit for conducting liquid refrigerant from the high pressure evaporator to the low pressure evaporator, the conduit including an insulated liquid reservoir above the level of the low pressure evaporator, and a portion exposed to a source of heat.

30 2. Refrigerating apparatus comprising in combination a relatively high pressure evaporator including a reservoir for liquid refrigerant, a relatively low pressure evaporator, and a conduit for conducting liquid refrigerant from the high pressure evaporator to the low pressure evaporator, the conduit including an insulated liquid reservoir above the level of the low pressure evaporator, and 40 a portion exposed to a source of heat.

35 3. Refrigerating apparatus comprising in combination a relatively high pressure evaporator including a reservoir for liquid refrigerant, a relatively low pressure evaporator, and a conduit for conducting liquid refrigerant from the high pressure evaporator to the low pressure evaporator and for cooling a compartment above the low pressure evaporator, the conduit including an insulated liquid reservoir in said compartment above the level of the low pressure evaporator, and 50 a portion exposed to a source of heat in said compartment above the level of the low pressure evaporator.

40 4. Refrigerating apparatus comprising in combination a relatively high pressure evaporator including a reservoir for liquid refrigerant, a relatively low pressure evaporator, and a conduit for conducting liquid refrigerant from the high pressure evaporator to the low pressure evaporator and for cooling a compartment above the low pressure evaporator, the conduit including an insulated liquid reservoir in said compartment above 45 the level of the low pressure evaporator, and

a portion exposed to a source of heat in said compartment above the level of the low pressure evaporator and means in the conduit for preventing the flow of liquid to the high pressure evaporator.

5. Refrigerating apparatus comprising in combination a relatively high pressure evaporator having a gas and liquid separating chamber, a relatively low pressure evaporator, a liquid inlet to said high pressure evaporator, and means responsive to the quantity of liquid in said chamber for controlling the passage of liquid thereto, a conduit leading below the level of liquid in the high pressure evaporator to the inlet of the low pressure evaporator, a liquid refrigerant reservoir interconnecting said conduit above said high pressure evaporator, said reservoir being adapted to receive its liquid refrigerant only due to the difference in pressures in said evaporators, said reservoir having a greater cross sectional area than said conduit, and means for controlling the admission of liquid to said low pressure evaporator, the apparatus being arranged to supply liquid refrigerant to said reservoir when the pressure differential is high to thereby provide for the supply of liquid to the low pressure evaporator when the pressure differential is low.

15 In testimony whereof I hereto affix my signature.
